MACHINE FOR CONVERGENT IRRADIATION

Josef Gerneth, Erlangen, Germany, assignor to
Siemens-Reiniger-Werke, Erlangen, GermanyApplication September 30, 1949, Serial No. 118,849
In Germany November 26, 1948

14 Claims. (Cl. 250—61.5).

1

This invention relates to a machine for convergent irradiation, and relates more particularly to a therapeutic device for treating inner organs of a human body by various types of irradiation, such as X-rays, electrons, neutrons, electro-magnetic radiation or ultra sound waves.

The term "convergent irradiation" is used throughout the specification and claims for the purpose of describing a therapeutic ray treatment, in the course of which the location of the source of the rays is shifted during irradiation in such manner that the rays directed to a specific organ pass consecutively through different locations upon the skin surface of the human body so as to protect the skin from detrimental effects.

An object of the present invention is the provision of a therapeutic device which is so constructed that the therapeutic rays are distributed over the largest possible skin surface of the human body at a constant distance of the source from the organ to be treated.

A further object is the provision of a therapeutic device which is so constructed that all parts of the body surface through which radiation is passed will be uniformly affected.

A further object is the provision of a therapeutic machine of the described type which is so constructed that one treatment with the machine moving in a determined direction can be followed immediately by a second treatment with the machine moving in an opposite direction.

Yet another object is the provision of a therapeutic machine of the described type, wherein irradiation at a time the source is immovable, is effectively avoided.

Still another object is the provision of a movable electrical radiation source which is so constructed that the twisting of the cable is effectively avoided.

Still a further object is the provision of a therapeutic device of the described type which is comparatively small in size, inexpensive to manufacture and most effective in operation.

Other objects of the present invention will become apparent in the course of the following specification.

The objects of the present invention may be realized through the provision of a device wherein the X-ray tube, or other source of irradiation, is moved automatically during the irradiation period upon a spherical surface, the center of the sphere coinciding with the location of the diseased part or organ to be treated, the rays being radially directed and describing a spiral upon the spherical surface. A uniform distance of the

2

source of irradiation from the organ to be treated and a distribution of the rays upon a large body surface are thereby attained. A uniform specific irradiation of all parts of this body surface can be achieved by increasing the speed of movement of the source with the diminishing radius of the spiral. In general it is advisable to select the speed of movement of the source in such manner that the treatment is completed while the rays move once over the entire spiral path. It is advisable to use as driving means a reversible electric motor so that a second irradiation having an opposed direction can immediately follow the first one. Furthermore, means should be provided to continue irradiation of the patient and to interrupt it as a result of the movement of the source, thereby avoiding the danger that irradiation may continue while the source is standing still. The switching on and off of the driving motor and the reversal of its movement can also be caused by the movement of the source, although care must be taken that the source is switched off prior to the switching of the motor. Since the source is usually supplied with electricity through a cable, it is advisable to avoid the winding of the cable by providing means which in the course of movement of the source prevent its rotation about an axis coinciding with the center ray thereof. Through the use of guiding means which turn the source to not more than 180° about the center ray thereof during the movement of the illumination along one-half of a winding of the spiral path, and which turn the source in the opposite direction during the movement of the illumination along the second half of the same winding, the apparatus may be made quite small, even when the source of the irradiation is an X-ray tube which extends in a direction perpendicular to the direction of the aforesaid center ray. An automatic shifting of the illumination along a spiral upon a spherical surface and a uniform distribution of the irradiation upon the human skin surface may be attained, by way of example, by the use of a circular guide along which the source is shifted by means of a motor during the irradiation, and which, at the same time, is driven to turn about an axis coinciding with the radius of the circular guide. The center of the circle must coincide with the location of the diseased part of the body.

The invention will appear more clearly from the following detailed description when taken in conjunction with accompanying drawings showing, by way of example, a preferred embodiment 55 of the inventive idea.

In the drawings:

Figure 1 is a longitudinal section through a device constructed in accordance with the principles of the present invention;

Figure 2 is a top view of the device shown in Figure 1, partly in section;

Figure 3 shows the entire device on a smaller scale and in longitudinal section along the lines 3—3 of Figure 4;

Figure 4 is a top view of the device on a smaller scale.

The machine shown in the drawings includes a casing 32 which contains an X-ray tube 9. The path of movement of the X-ray tube is provided by two curved rails 1, the center of the curvature of which is designated by the numeral 11. The two rails 1 are located in parallel planes, and their legs are directed toward each other. The rails 1 are provided with flanges 2 carrying bolts 2a and mounted upon a ring 3.

As shown in Figures 1 and 2, the ring 3 is U-shaped in cross-section, and carries four rollers 4 which are rotatably mounted upon pivots 4a carried by the ring 3.

The rollers 4 are supported within a guide 5 of annular form, which is rotatable about an axis 10, as will appear in detail hereinafter. For the sake of clarity parts of the member 5 are shown as being broken off in Figure 2.

A so-called compression tube 30, shown in Figures 1 and 3, is connected to the bottom surface of the guide 5.

The guide 5 is firmly connected with the casing 32 which is firmly connected with a projecting arm 6.

The arm 6 may be attached to a bracket not shown in the drawings, and adjustable in a vertical direction.

The X-ray tube 9 is firmly mounted upon a carriage 7 provided with rollers 8. The X-ray tube 9 carries a conical tube 12 which is firmly connected therewith. The X-ray tube 9, with the tube 12, are rotatable about an axis 31, which coincides with the central ray emitted by the X-ray tube.

In Figure 1 the tube 9 is illustrated in one of its end positions upon the rail 1, while Figure 2 shows the tube in its other end position.

The right-hand side of the rails 1 (looking in the direction of Figures 1 and 2) is firmly connected with the casing 13, carrying the driving motor 14. The motor 14 is supplied with electric power by means not illustrated in the drawings—for example, through contact rings supplied with electricity through an insulated ring located at the bottom of the ring 3.

It should be noted that the motor 14 and the casing 13 are located upon one side of the guides 1, while the carriage 7 moves upon the other side of the guides 1. This arrangement provides a more uniform distribution of weight upon the ring 3.

The motor 14 has a motor shaft 15 which carries a worm 16, meshing with a gear 17, keyed upon a shaft 18.

The shaft 18 is firmly connected with a pinion 19 meshing with a toothed crown 20, which is located upon the upper edge of the guide 5, and is firmly connected therewith. Furthermore, the shaft 18 is firmly connected with a cone gear 21 meshing with a gear 21a which is keyed upon the shaft 23 (Figs. 1, 2, 5 and 6). The shaft 23 is rigidly connected with a worm 23a meshing with a gear 22. The gear 22 is keyed upon a shaft 24, which is thus slowly rotated by the motor 14. 75

The shaft 24 carries cams 25 and 26 which are located upon the ends of the shaft 24, and are rotated thereby. The cams 25 and 26 are connected with ropes, strings or chains 27 and 28, respectively. The member 27 is attached directly to the carriage 7, while the member 28 is passed over a pulley 29 which is mounted upon the ring 3 and is located substantially opposite the cam 26. Thus, the member 28, which is also attached to the carriage 7, pulls the carriage in the opposite direction from that of the member 27. As the shaft 24 is rotated the extent of winding of one of the members 27 or 28 is the same as the extent of unwinding of the other member. Due to this arrangement, the carriage 7, along with the X-ray tube 9 carried thereby, is prevented from being shifted involuntarily throughout its various positions in the course of radiation.

20 The guides 1 carry contacts which are not illustrated in the drawings, and which engage other contacts carried by the X-ray tube (also not shown), so that the X-ray tube is switched on automatically shortly after the beginning of the movement of its carriage upon the guides. The X-ray tube is switched off automatically by similar means shortly before the end of the movement of the carriage upon the guides. Similar contacts (not shown) may be used to switch off the motor 14 or to reverse its direction of rotation when the carriage 7 has reached the position shown in Figure 2.

The driving motor 14 is preferably provided with a centrifugal regulator.

35 The spiral movement of the X-ray tube is attained in the following manner:

When the motor is switched on it drives the shaft 18 by means of the motor shaft 15, the worm 16 and the gear 17. The shaft 18 drives, on the one hand, the pinion 19, which meshes with the crown 20 and thereby causes a rotation of the ring 3 with the guides 1 carried thereby about the axis 10.

On the other hand, the shaft 18 drives the cams 25 and 26 through the worm 21, the gear 21a, the shaft 23, the worm 23a, the gear 22 and the shaft 24, the rotation of the cams 25 and 26 being considerably slower than the rotation of the ring 3 (Figs. 1, 2, 5 and 6). The cams 25 and 26 operate the pulling members 27 and 28 so that the carriage 7 with the X-ray tube is moved slowly along the guides 1 while these guides are being rotated by the ring 3. The form of these cams 25 and 26 is so selected that the speed of movement of the carriage 7 increases steadily with a decrease in the radius of the spiral. It is apparent that this spiral path is carried out by the X-ray tube as a result of the combined movements along the guides 1 and about the axis 10. Due to the variation in the form of the cams 25 and 26 the specific irradiation of all parts of the outer surface of the body to be treated remains the same.

65 Figure 3 shows two positions of the X-ray tube 9, the second position being illustrated by broken lines.

Figure 4 shows by broken lines six different positions of the X-ray tube.

The X-ray tube 9 carries two guide rolls 33 which roll upon the inner surfaces of the casing 32, namely, upon the left side of the casing (looking in the direction of Figure 3). During this rolling movement of the rollers 33, the X-ray tube moves along one-half of the winding of the spiral, and, at the same time, turns about the central

ray axis 34 to the extent of 180°, producing a slight twist of the cables leading to the X-ray tube and not shown in the drawings.

On the other hand, the right-hand side of the casing 32 is square (Figure 4); and is of such dimensions that the X-ray tube 9 can turn conveniently about the axis 34. Thus, the slight twist imparted during the movement of the X-ray tube along the first half of a winding of a spiral is easily eliminated during the movement along 10 the second half of the same winding.

It is apparent that the example above shown has been given solely by way of illustration and not by way of limitation, and that it is subject to a number of variations and modifications, without departing from the scope or method of the present invention.

For example, a toothed rail having the form of a spiral may be affixed to the inner surface of a sphere and the motor with the X-ray tube hanging therefrom may be moved along the rail by means of a motor-driven pinion. All such and other variations and modifications are to be included within the scope of the present invention.

What is claimed is:

1. A therapeutic machine for convergent irradiation, comprising in combination with a source of irradiation, two U-shaped circularly curved guides extending parallel to each other and with their legs directed toward each other, means moving said source upon said guides; means rotating said guides, a casing enclosing said guides; rollers carried by said source, said casing having a guide formed upon inner surfaces thereof and engaged by said rollers during one half of a winding of the spiral path of said source in relation to said casing, to cause a rotation of said source to an angle of 180° about an axis coinciding with the central ray of the radiation of said source, said rollers being devoid of contact with the last-mentioned guide during the other half of said winding.

2. An apparatus for irradiating a diseased organ located within the body of a patient with therapeutically operative rays, comprising in combination with a source of rays, means automatically moving said source during irradiation upon a spherical surface having a center coinciding with said organ, means connected with the first-mentioned means and directing said rays radially toward said center, and means connected with the first-mentioned means and guiding said source along a spiral path.

3. An apparatus for irradiating a diseased organ located within the body of a patient with therapeutically operative rays, comprising, in combination with a source of rays, a circularly curved guide, means movably supporting said source upon said guide, means connected with the first-mentioned means and directing the rays thereof to the center of the circular curvature of said guide, automatically operable means connected with said source and moving said source along said guide during irradiation, and automatically operable means connected with said guide and rotating said guide about an axis which constitutes a radius of said circular curvature, whereby said source will describe a spiral path.

4. An apparatus for irradiating a diseased organ located within the body of a patient with therapeutically operative rays, comprising in combination with a source of rays, a circularly curved guide for the source, means movably supporting said source upon said guide and di- 75

recting the rays thereof to the center of the circular curvature of said guide, a ring carrying said guide, said ring being rotatable about an axis constituting a radius of said circular curvature, a motor rotating said ring during illumination, and automatically operable means moving said source along said guide during irradiation.

5. An apparatus for irradiating a diseased organ located within the body of a patient with therapeutically operative rays, comprising in combination with a source of rays, a circularly curved guide for the source, means movably supporting said source upon said guide and directing the rays thereof to the center of the circular curvature of said guide, a ring carrying said guide, said ring being rotatable about an axis constituting a radius of said circular curvature, a stationary toothed crown enclosing said rotatable ring, a motor mounted upon said ring, a gear driven by said motor and engaging said crown to rotate said ring and said guide during illumination, and a drive connected with said motor and said source to move said source upon said guide during illumination.

6. An apparatus for irradiating a diseased organ located within the body of a patient with therapeutically operative rays, comprising in combination with a source of rays, a circularly curved guide for the source, means movably supporting said source upon said guide and directing the rays thereof to the center of the circular curvature of said guide, a ring carrying said guide, said ring being rotatable about an axis constituting a radius of said circular curvature, a stationary toothed crown enclosing said rotatable ring, a motor mounted upon said ring, a pinion driven by said motor and engaging said crown to rotate said ring and said guide during illumination, a pulley rotated by said motor during illumination, and a flexible pulling element having one end connected with said source and another end connected with said pulley and being wound upon said pulley during rotation thereof to pull said source upon said guide.

7. An apparatus for irradiating a diseased organ located within the body of a patient with therapeutically operative rays, comprising in combination with a source of rays, a circularly curved guide for the source, means movably supporting said source upon said guide and directing the rays thereof to the center of the circular curvature of said guide, a ring carrying said guide, said ring being rotatable about an axis constituting a radius of said circular curvature, a stationary toothed crown enclosing said rotatable ring, a reversible motor mounted upon said ring, a pinion driven by said motor and engaging said crown to rotate said ring and said guide during illumination, a pulley rotatable by said motor during illumination, and two flexible pulling elements having ends connected to opposed sides of said source corresponding to directions of movement thereof and other ends connected with said pulley, whereby one of said pulling elements pulls said source upon said guide during rotation of said pulley.

8. An apparatus for irradiating a diseased organ located within the body of a patient with therapeutically operative rays, comprising in combination with a source of rays, a circularly curved guide for the source, means movably supporting said source upon said guide and directing the rays thereof to the center of the circular curvature of said guide, a ring carrying said

guide, said ring being rotatable about an axis constituting a radius of said circular curvature, a stationary toothed crown enclosing said rotatable ring, a reversible motor mounted upon said ring, a pinion driven by said motor and engaging said crown to rotate said ring and said guide during illumination, a pulley rotatable by said motor during illumination, two flexible pulling elements having ends connected to opposed sides of said source corresponding to directions of movement thereof and other ends connected with said pulley, whereby one of said pulling elements pulls said source upon said guide during rotation of said pulley, and means reversing said motor at predetermined locations of said source upon said guide.

9. An apparatus for irradiating a diseased organ located within the body of a patient with therapeutically operative rays, comprising in combination with a source of rays, means connected with said source and automatically moving said source during irradiation upon a spherical surface having a center coinciding with said organ, means connected with said source for directing said rays radially toward said center, means guiding said source along a spiral, and means connected with the first-mentioned means and increasing the speed of movement of said source as the radius of said spiral is decreased.

10. An apparatus for irradiating a diseased organ located within the body of a patient with therapeutically operative rays, comprising in combination with a source of rays, means automatically moving said source during irradiation upon a spherical surface having a center coinciding with said organ, means connected with the first-mentioned means for directing said rays radially toward said center, means guiding said source along a spiral, and means connected with said source and switching on and off said irradiation depending upon the movement of said source.

11. An apparatus for irradiating a diseased organ located within the body of a patient with therapeutically operative rays, comprising in combination with an electrically movable source of rays, a circularly curved guide for the source, means movably supporting said source upon said guide and directing the rays of the source to the center of the circular curvature of said guide, a ring carrying said guide, said ring being rotatable about an axis constituting a radius of said circular curvature, a motor rotating said ring during irradiation, automatically operable means moving said source along said guide during irradiation, means automatically switching on and off the electrical current for said source depending upon movements of the source, and means switching off said motor in predetermined positions of said source upon said guide.

12. An apparatus for irradiating a diseased organ located within the body of a patient with therapeutically operative rays, comprising in combination with a source of rays, means automatically moving said source during irradiation upon a spherical surface having a center coin-

ciding with said organ, means guiding said source along a spiral path, means directing said rays radially toward said center, and means preventing said source from turning more than 180° about the central ray thereof during the movement of said source.

13. An apparatus for irradiating a diseased organ located within the body of a patient with therapeutically operative rays, comprising in combination with a source of rays, a circularly curved guide for the source, means supporting said source upon said guide for rotation about the central ray of said source and for movement along said guide with said rays being directed to the center of the circular curvature of said guide, automatically operable means moving said source along said guide during irradiation, automatically operable means rotating said guide about an axis which constitutes a radius of said circular curvature, and guide means operable during each rotation of said guide by 360° to turn said source about its central ray to an angle of 180° during the guide rotation ranging from 0° to 180° and releasing said source during the guide rotation ranging from 180° to 360°.

14. An apparatus for irradiating a diseased organ located within the body of a patient with therapeutically operative rays, comprising in combination with a source of rays, a circularly curved guide for the source, means supporting said source upon said guide for movement along said guide and rotation about the central ray of said source and directing the rays of the source to the center of the circular curvature of said guide, automatically operable means moving said source along said guide during irradiation, automatically operable means rotating said guide about an axis which constitutes a radius of said circular curvature, a casing enclosing said guide, and rollers carried by said source, said casing having a fixed guide formed upon an inner surface thereof and guiding said rollers during each rotation of the guide by 360° solely in the range of 0° to 180° and thereby causing a turning of said source about its central ray to an angle of 180°.
